US0D1084007S

(12) **United States Design Patent** (10) **Patent No.:** **US D1,084,007 S**
Helzer et al. (45) **Date of Patent:** **** Jul. 15, 2025**

(54) **DISPLAY SCREEN OR PORTION THEREOF WITH GRAPHICAL USER INTERFACE**

(71) Applicant: **IGT**, Las Vegas, NV (US)

(72) Inventors: **Daniel Helzer**, Reno, NV (US);
Gianpaulo Sorreta, Sparks, NV (US);
Bradford Brown, Sparks, NV (US)

(73) Assignee: **IGT**, Las Vegas, NV (US)

(**) Term: **15 Years**

(21) Appl. No.: **29/812,877**

(22) Filed: **Oct. 25, 2021**

Related U.S. Application Data

(62) Division of application No. 29/685,934, filed on Apr. 1, 2019, now Pat. No. Des. 936,074.

CLAIM

The ornamental design for a display screen or portion thereof with graphical user interface, as shown and described.

DESCRIPTION

The FIGURE is a front view of a display screen or portion thereof with graphical user interface showing our new design.

The broken lines showing the display screen or portion thereof with a graphical user interface illustrate portions of the article, and form no part of the claimed design.
